UNITED STATES PATENT OFFICE

2,677,734

ELECTRIC CIRCUIT BREAKER

William D. Boller, Milford, Ohio, Warren D. Berkley, Fort Wayne, Ind., Walter Ernst, Dayton, Ohio, and Edwin W. Landmeier, Covington, Ky., assignors to The Wadsworth Electric Mfg. Co., Covington, Ky., a corporation of Kentucky

Original application June 10, 1948, Serial No. 32,204, now Patent No. 2,618,716, dated November 18, 1952. Divided and this application February 16, 1952, Serial No. 274,247

3 Claims. (Cl. 200—88)

1

This invention relates to circuit breakers, and is concerned primarily with a circuit breaker intended to control the circuits in homes and comparable places.

This application is a division of our United States patent application Serial No. 32,204, which was filed June 10, 1948, for "Electric Circuit Breaker," and which is now issued as United States Patent No. 2,618,716.

At the present time, the electrical installations for homes, business establishments, and other places making use of the current supply that is made available by the electric companies includes one or more circuits, each of which embraces a fuse and sometimes a switch associated therewith. When the circuit is overloaded or a short circuit develops, the fuse burns out in a well-known manner and must be replaced before service can be restored.

The present invention has in view as its foremost objective the provision of a circuit breaker which is intended to replace the fuse and switch heretofore employed in controlling such circuits.

Under practical conditions, a plurality of circuits are ordinarily included in electrical installations of the type with which this invention is concerned and a further object of the invention is the provision of a circuit breaker which is susceptible of being assembled in multiple or gangs with each unit controlling one circuit.

In the known combination units of the type intended to be improved by this invention, it has been the practice to provide a pair of contacts for controlling the circuit. When these contacts are in engagement, the circuit is closed and when they are spaced apart, the circuit is open. Usually one of these contacts is fixed and the other is movable. The present invention has in view as an important object the provision of a circuit breaker of the type indicated in which both of the contacts are movable. This arrangement presents certain definite advantages. It is possible to provide for the movement of one contact into opened or closed position under the influence of a manually operable lever while the other contact is placed under the control of the circuit conditions so as to be moved into opened position under overload or short circuiting conditions. This latter contact may be moved back into circuit closing position under the influence of the manually operable lever.

The problem of eliminating arcing in a circuit breaker of this type has long been recognized by those skilled in this art. When the two contacts move apart an arc is created due to ionization of

2

the air and numerous and varied attempts have been made in devising means for eliminating this arcing. The present invention has in view as another highly important object the provision of new and improved means for eliminating the arcing. In achieving this end, a permanent magnet is employed and is located in close proximity to the movable contacts. This permanent magnet has a magnetic strength that is sufficient to

10 be effective on the arc which is created by the break of the contacts. This arc will depend on the current and speed at which the contacts are moved apart. Thus, when the contacts move apart any arc which might be created is drawn

15 to the permanent magnet and eliminated. This action is characteristically different from those devices which operate on the principle of snuffing out the arc by depriving it of air.

To the end of keeping the contacting surfaces 20 clean a further object of the invention is the provision of a circuit breaker of the type indicated in which the contacts are separated with a wiping action in contrast to a direct pull apart.

Another object of the invention is the provision of fiber shielding on the casing structure 25 immediately about the arc suppressing magnet. This shielding accommodates the formation of carbon deposits on the interior of the casing and cover.

30 Various other more detailed objects and advantages of the invention such as arise in carrying out the above noted ideas in a practical embodiment will in part become apparent and in part be hereinafter stated as the description of the invention proceeds.

35 For a full and more complete understanding of the invention reference may be had to the following description and accompanying drawings wherein:

40 Figure 1 is a longitudinal vertical section through a circuit breaker designed in accordance with the precepts of this invention and showing the unit in manually closed position;

45 Figure 2 is a sectional view similar to Figure 1 showing the unit in the manually opened position;

Figure 3 is another view similar to Figures 1 and 2 showing the unit in the opened position as caused by circuit conditions;

50 Figure 4 is a vertical section taken on a plane normal to the showing of Figures 1, 2 and 3;

Figure 5 is an enlarged detailed view showing the rocker carrying one of the contacts in plan and the casing in section; and

55 Figure 6 is another detailed view taken on a

horizontal plane as represented by the line 6—6 on Figure 1.

The preferred embodiment of the invention is illustrated in Figures 1 to 6, inclusive. In these views there is shown a casing which is referred to in its entirety by the reference character C and which is made from an appropriate material having good insulating properties and which is susceptible of being molded into the desired structural formation. There are available on the public market many synthetic plastics which will fulfill these qualifications. Among these is the phenol condensation product known as Bakelite.

The casing C comprises a main side wall 10, a top wall 11, a bottom wall 12, and end walls 13 and 14 which are spaced inwardly from the end edges of the side wall 10. All of these walls are integrally joined and the completed structure provides free end portions of the side wall 10 which are represented at 15 and 16 and immediately beneath which are the thickened wall structures 17 and 18.

The end wall 13 is formed with a slot 19 which defines an outer panel 20 which is relatively long and the end edge of which is spaced from the thickened wall structure 17. This slot 19 also defines an inner panel 21 which is relatively short and the end edge of which defines an opening at 22. A terminal plate 23 is formed at one end with an inclined flange 24 which is received in the slot 19. This terminal plate 23 is also formed with a neck 25 which is countersunk in a recess formed in the thickened wall structure 17. This neck 25 is interiorly threaded as represented at 26 to accommodate a binding post. The thickened wall structure 17 is also provided with a recess 27 beneath the threaded bore 26 to allow for screwing the binding post (not illustrated) home.

Referring now to the thickened wall structure 18 and end wall 14, it will be noted that these two elements are spaced apart by an irregularly shaped slot 28. The wall structure 18 is formed with a recess 29 that is counterbored as indicated at 30. Another terminal plate 31 has a neck 32 that is received in the counterbore 30 and the bore of which is threaded as indicated at 33, the threaded bore being located opposite to the recess 29. The threaded bore 33 and recess 29 accommodate another binding post. The terminal plate 31 is formed with an irregularly shaped part 34 that corresponds to and is received in the slot 28. Integrally connected to this part 34 is a flange 35 which is positioned within the chamber enclosed by end walls 13 and 14.

An adjusting screw 36 is received in a passage 37 formed in the thickened wall structure 18. This screw 36 has a head 38 which is positioned within an enlarged recess 39 that communicates with the bore 37. This head 38 may be slotted to accommodate a tool such as a screw driver.

The thickened wall structure 18 is formed with a recess 40 which communicates with the inner chamber of the casing and the bore 37. The adjusting screw 36 extends into this recess and immediately adjacent to the thickened wall 18 is formed with an annular groove 41 which receives a washer 42. This washer 42 and the head 38 hold the screw 36 against longitudinal movement. The free inner end of the screw 36 is threaded and screwed into an opening 43 formed in the flange 35 and also into an opening 44 formed in the end portion 45 of a bimetallic thermostat 46, this end portion 45 being offset from the main part of the bimetallic thermostat 75

by a shoulder 47. It will be noted that this end portion 45 snugly engages the flange 35 of the terminal plate and is spot welded thereto.

Extending inwardly from the end wall 14 into the inner chamber are a pair of lugs 48 and 49 which are integrally formed with the wall 14. The opposing corners of these lugs 48 and 49 are cut away to provide recesses which receive a rupture magnet 50. This magnet 50 is of the U-shaped cross-section illustrated in Figure 6 and has legs 51 and 52, the outer faces of which are imbedded in the side wall 10 and cover to be later described. These side legs 51 and 52, together with the base, define a recess 53 through which the bimetal 46 passes. It is evident that current passing through the bimetal 46 will be effective on the rupture magnet 50 to vary the strength thereof for circuit rupturing purposes as will be later described.

A keeper piece 54 has its lower end anchored to the end part 45 of the bimetal 46 in any preferred manner such as by being spot welded thereto. The upper end of this keeper piece takes the form of a hook 55, to the bill of which overlaps the end of the bimetallic thermostat 46. A latch member 56 which also functions as an armature for the magnet 50 is secured to this keeper piece 54. This latch member 56 is made from a metal having the required magnetic properties and it will be noted that a detent 57 is struck therefrom as by a metal stamping operation. The anchorage between the latch 56 and the keeper piece 54 is effected by punching a pair of recesses 58 in one face of the latch 56. This forms small protuberances 59 on the opposite face. The keeper piece 54 is formed with openings which receive these protuberances 59. After the protuberances 59 pass through the openings they are peened over to form what are in effect rivet heads 60.

The bottom wall 12 is formed with an inclined surface at 61 which opens into the inner chamber and which terminates at its lower end in a shoulder 62. A permanent magnet 63 of U-shaped formation has its base received on the inclined surface 61. The side legs of the magnet 63 have outer faces which are received in recesses 64 and 65 formed in the casing and cover, respectively. Also, fitted in these recesses and surrounding the sides of the magnet 63 are fiberboard frames 66 and 67 which are held in position by lugs 68 that are formed integral with the cover and casing respectively and which have end portions that overlap the fiberboard frames.

The permanent magnet 63 is intended for arc suppressing purposes as will be later described and the fiberboard frames 66 and 67 accommodate the arc deposits which are formed by carbonizing which is an incident to the arc suppression. At this point, it is well to note that the strength of the permanent magnet 63 is related to the magnitude of the arc which will be created by the break of the contacts. The magnitude of the arc depends on the speed at which the contacts are broken and the strength of the current. There are now available permanent magnets having this required strength. Among such are the magnets sold under the trade name "Alnico."

Extending downwardly from the top wall 11 into the inner chamber is a projection 69 having an end face at 70 which is adapted to act as an abutment or stop as will be later described. This top wall 11 is also formed with an opening at 71, the end walls of which are formed as the cylind-

drical surfaces illustrated in the drawing. A manually operable lever 72 is formed with diametrically opposite projections 73 at each side thereof and these projections act as trunnions or pivots for mounting the lever 72. They are received in recesses 74 formed in the casing and cover, respectively, along the side edges of the opening 71. This lever 72 carries an arcuate wall structure 75 which is complementary to and snugly received within the curved end walls of the opening 71. This wall structure 75 completely closes the opening and at the same time permits swinging of the lever 72 about the trunnions 73 as a pivotal mounting.

Extending inwardly into the inner chamber and carried by the lever 72 are a pair of legs 76 which are spaced apart with the lower free edge of each leg formed with a notch 77. The inner face of each leg 76 is also formed with a V-shaped notch presenting inclined faces 8 and 7 that terminate at the lower edges of the leg. Thus the V-shaped notches are wider than the notches 77 and the faces 8 and 7 are adapted to function as stops in a manner now to be described.

A contact carrier 78 is of bifurcated construction defining a pair of legs 79 and 80 which are integrally joined at the bottom and from each of which outstands a pin 81 that is received in the respective notch 77. The lower end of this contact carrier 78 carries a contact 82. A tension coil spring 83 has its lower end anchored to the contact carrier 78 as represented at 84. The other end of this spring 83 is anchored to a rocker now to be described. It is evident that movement of carrier 78 about pins 81 is limited by the stop faces 8 and 7 on the legs 76.

A rocker 85 has trunnions 86 extending from opposite sides thereof and these trunnions are journaled in the cover and casing respectively as is brought out in Figure 5. The lower end of this rocker 85 carries a contact 87 which is complementary to and adapted to engage the contact 82. It is notable that the contact 82 is moved away from the contact 87 by a wiping action caused by the straightening of the lever 72 and carrier 78. This rocker is made of a good conducting material such as copper and its upper end is reduced in size to provide for the mounting of an insulating member 88 thereon. This insulating member may take the form of a glass ring and it functions as an insulated anchorage for the upper end of the spring 83. Mounted on opposite faces of the rocker 85 are a pair of brackets 89 and 90, the connection being effected by spot or resistance welding; the hole shown at 91 in Figure 5 serving as a locating point. Each of these brackets 89 and 90 is formed with a cam surface 9 which is adapted to cooperate with the respective side edge 92 of the leg 76.

The rocker 85 also carries an outwardly extending projection 93 having a face at 94 that is adapted to engage the abutment face 70. A flexible conductor 95 connects this projection 93 on the rocker 85 with the bimetal 46. Another flexible conductor 96 connects the contact carrier 78 with the terminal plate 23 passing through the opening 22 and being joined to the flange 24 in any preferred manner as by soldering.

The cover is shown at 97 and is preferably made from an insulating material having transparent properties and which is susceptible of being tinted to a desired shade for the purpose of designating the capacity of the unit. It will be noted that the end wall 13, thickened wall structure 17, thickened wall structure 18, and

projection 69 are formed with openings, all of which are designated 98. The cover 97 is formed with openings that align with openings 98 and tubular fastening members 99 pass through the aligned openings. The ends of these tubular fasteners may be peened outwardly in a well-known manner to provide what is in effect a riveted connection.

Operation of the device

In outlining the operation of the above described circuit breaker, attention is first called to Figure 1 which depicts the condition of the unit when the circuit is closed. It will be noted that in this position the spring 83 being disposed at one side of the pins 81 urges the contact 82 against the contact 87 because movement of the rocker is prevented by the detent 57 which is in engagement with the surface 94 of the projection 93. In this position the upper end portion of the carrier 78 is in substantial engagement with the stop face 7. Under this condition, current will pass from the terminal plate 31 through the flange 35 thereof to the bimetal 46, conductor 95 connects the latter to the rocker 85. The current then passes from the rocker 85 through contacts 87 and 82 to contact carrier 78 and from there through the conductor 96 to the terminal plate 23.

Figure 2 depicts the unit in the condition in which the circuit has been opened by manual operation of the lever 72. It will be noted that the contacts 82 and 87 have been moved apart with a wiping action to break the circuit. This has been achieved by movement of the contact 82 alone because the latch 57 still holds the rocker 85 against movement. As the lever 72 is swung from the position shown in Figure 1 to that shown in Figure 2, the pivot point 81 passes from the left-hand side of the center line of the spring 83 (speaking with reference to the showing of the drawings) to the right-hand side. This causes the spring 83 to bias the contact 82 away from the contact 87. It will be noted that this movement on the part of the lever 72 is accommodated because there is an appreciable space between the cam surfaces 92 and 9. Thus, the lever may be moved without affecting the rocker 85. In this position the upper end of the carrier 78 engages the stop face 7.

Figure 3 shows the condition of the unit which has been caused by circuit conditions to rupture the circuit by moving both the contacts 82 and 87. The circuit condition might either be an overload which affects the bimetallic thermostat 46 so as to move the keeper piece 54 and latch 56 carried thereby so that the detent 57 is withdrawn from the projection 93 or it may be a short circuit which will cause the rupture magnet 60 to have this effect on the latch member 56 which, it will be recalled, is also an armature for the magnet. Regardless of which may be the cause, when the detent 57 is withdrawn from the projection 93, the spring 83 being always under tension rotates the rocker 85 in a counterclockwise direction (speaking with reference to the showing of the drawings) and this movement is continued until the surface 94 engages the abutment surface 70. As this movement takes place, the contact 87 of course moves away from the contact 82. At the same time, the pivot pin 81 will be effected by the movement of the rocker arm to change its relative position with respect to the spring 83 and instead of being positioned on the left-hand side, as in the circuit closing

position, its relative position is changed to the right-hand side and the contact 82 is also moved in the direction away from the contact 87.

As the contacts 82 and 81 move away from each other there ordinarily would be a tendency to arcing. However, this arcing is suppressed by the permanent magnet 63.

The position of the lever 72 after the circuit has been ruptured by circuit conditions is shown in Figure 3 which, it will be noted, is substantially intermediate the positions of Figures 1 and 2. In this position the cam surfaces 92 and 9 are in close proximity. Thus, when it is desired to reset the unit to close the circuit the lever 72 must first be swung in a counterclockwise direction to move the rocker 85 in a clockwise direction and again place the projection 93 under the retaining effect of the detent 57 of the latch 56. The lever 72 may then be swung into the circuit closed position shown in Figure 1.

What is claimed is:

1. An electric circuit breaker comprising, bottom, side and top wall members providing a casing, a contact carrier and a rocker member pivotally mounted in said casing and having respective contacts which are cooperable with one another, the said contact carrier being manually operable for contact engagement and disengagement, and the said rocker being automatically operable in response to circuit overload conditions to disengage the contacts, and means for minimizing the adverse effects of arcing developed upon engagement and disengagement of the said contacts, comprising, a shoulder on the bottom wall member of said casing, a permanent magnet mounted on the bottom wall of said casing member, in endwise abutment with said shoulder, and having its midpoint approximately coinciding with the line at which the contacts engage one another, the said magnet extending along opposite sides of the respective paths of movement of the contact carrier and rocker when they are disengaged, the said permanent magnet being substantially U-shaped in cross section and having sidewise portions residing closely adjacent the sidewise portions of said contacts when the latter are in engagement, whereby the magnetic field of the permanent magnet cuts directly across the paths of movement of the said carrier and rocker contacts, the said casing side wall members having recesses therein engaging the external surfaces of said magnet sidewise portions.

2. An electric circuit breaker comprising, a casing having a contact carrier and a rocker 55

member pivotally mounted therein, contacts mounted respectively upon said carrier and rocker, means for moving said carrier to contact engaging and disengaging positions manually, 5 and means for moving said rocker to contact disengaging position automatically in response to circuit overload conditions, the said casing having a seat recess therein adjacent the point at which the contacts reside in engagement, a magnet member seated in said recess and secured thereby, the said magnet member having portions respectively extending along the paths through which the contact carrier and rocker move toward contact disengaging positions, the said magnet portions straddling the respective contacts of the carrier and rocker, whereby the magnetic field of said magnet means is exerted directly across the paths of travel of the respective contacts in their movement toward and from engagement.

3. An electric circuit breaker comprising, a casing having a contact carrier and a rocker member pivotally mounted therein, contacts mounted respectively upon said carrier and rocker, means for moving said carrier to contact engaging and disengaging positions manually, 25 and means for moving said rocker to contact disengaging position automatically in response to circuit overload conditions, the said casing comprising bottom and side wall members configurated to provide a seat recess therein adjacent the point at which the contacts reside in engagement, a magnet member seated in said recess and secured thereby, the said magnet member having portions respectively extending along the paths through which the contact carrier and rocker move toward contact disengaging positions, the 30 said magnet portions straddling the respective contacts of the carrier and rocker, whereby the magnetic field of said magnet means is exerted directly across the paths of travel of the respective contacts in their movement toward and from engagement, the said casing also having 35 shielding members residing adjacent the side walls thereof above said magnet and beyond the endwise portions thereof.
